UNITED STATES PATENT OFFICE.

JOHN J. RYAN AND JOHN GAFFNEY, OF NEW HAVEN, CONNECTICUT, ASSIGNEES TO
NATIONAL FOLDING BOX COMPANY, OF NEW HAVEN, CONNECTICUT, A CORPORATION OF NEW JERSEY.

DISPLAY CARTON.

Application filed April 17, 1925. Serial No. 23,748.

Our present invention relates to an advertising and display carton formed from cardboard or like material and to a blank from which such a carton is formed.

5 The invention relates more expressly to a carton or pasteboard box for advertising purposes which may when desired be used for holding articles that are to be advertised or that are to be sold and which has 10 formed as a part thereof a plate or extension having a surface that may be held in position for advantageous display and advertising. All of the exposed surfaces of the carton are used for carrying printed matter 15 or the like for advertising purposes and means are provided for tilting the carton to a suitable angle to display the top of the box to the best advantage. Preferably the extension simulates a cover and is provided 20 with means for holding it as in an open position upstanding with respect to the upper surface of the carton. In such cases the printed display on said top surface of the carton may resemble one or a plurality of 25 articles which the box is advertising so that the finished carton has the appearance of an open box containing the articles advertised.

In the accompanying drawing which 30 forms part of this application,

Fig. 1 is a perspective view showing what appears to be an open box with printed matter on the inside surfaces of the cover, and printed matter on the actual upper surface of the carton simulating articles which the carton is supposed to contain, and extensions on the end members of the carton which serve to hold the box tilted upwardly 35 toward the back. This being a perspective view but one of the supporting members is shown.

Fig. 2 is a plan view of the developed blank from which the carton is formed.

In Fig. 1 of the drawing the top surface 1 of the carton has printed thereon a simulation of smaller cartons 2, 2 and presents the appearance of a plurality of such smaller cartons 2, 2 as being assembled in ordered arrangement within the main carton. Extending upwardly from the back of the box and preferably formed continuous with said top surface 1 is the flap 3 which in Fig. 1 is held at such a position and is of such a size as to simulate a cover for said main 55 carton. On said flap 3 is printed adver-

tising matter of desired character. In this preferred embodiment of my invention there is formed along the upper edge of the back member 4, of the box a tab 5 which extends substantially the length of the flap 3 and 60 is fastened thereto by gluing or clipping and serves to stiffen and hold flap 3 in the desired position. The front surface 6 of the carton is also used to carry advertising characters. At the bottom edge of each 65 of the end members 7, 7 of the carton, only one which appears in the perspective view of Fig. 1, is formed a downward extension 8 which has a greater width at the back than at the front and which in this form 70 serves to hold the carton tilted upwardly from the back whereby the top surface 1 of the carton is more fully exposed (and more readily seen).

In Fig. 2 is shown a development of the 75 blank from which the carton of the preferred embodiment of our invention in Fig. 1 is formed. In this figure is shown the top member 1 connected to the bottom member 9 by a front portion 6, 6 and a flap 80 extension 3 formed on the back edge of said top portion 1. This flap extension 3 is of substantially the same length and width as the said top portion. From the back edge of the bottom portion 9 extends a back 85 portion 10 which carries at its outer edge a tab 5 which extends substantially the length thereof and is of appreciable width itself. At the ends thereof said bottom portion 9 carries end portions 12, 12 having 90 flaps 13, 13 thereof for folding into the box and holding the end portions 12, 12 in place. At its ends the top portion 1 carries end portions 14, 14 having the end flap portions 15, 15 for folding into the 95 box and holding the respective end portions 14, 14 in place and also carrying at their lower edges extensions 8, 8 which have a greater width at the back thereof than at the front. These latter extensions serve 100 as shown in the description of Fig. 1 to support the finished carton in the tilted position. Said flap extension 3 on the top portion 1 serves in the finished carton to simulate a cover for the box which is in 105 the open position, and said tab 5 on the upper edge of the back portion serves as above described to support said flap extension in the simulated open position of the simulated cover.

It is to be understood that various modifications of our invention as shown, described, and hereinafter claimed may be made without departing from the spirit of our invention.

We claim:

1. As an article of manufacture, a carton blank having a bottom section, a top section, a front section intermediate and unitary with bottom and top sections, a back section, end sections at each end of the bottom section, tabs formed on the edges of said end section opposite said bottom section for folding into the carton, an end section at each end of said top section having tabs thereon for folding into the carton and an extension which projects further from said end section at given points than at other points and a tab formed as a backward extension of said top section, said top being printed to simulate articles in the carton and said tab being printed with an advertising display.
2. As an article of manufacture, a carton blank having a bottom section, a top section, a front section intermediate and unitary with said bottom and top sections, a back section, end sections at each end of bottom section, tabs formed on the edges of said end section opposite said bottom section for folding into the carton, an end

section at each end of said top section having tabs thereon for folding into the carton and each having an extension having a greater width at the back edge thereof than at the front edge and a tab formed as a backward extension of said top section, said top being printed to simulate articles in the carton and said tab being printed with an advertising display.

3. As an article of manufacture, a carton blank having a bottom section, a top section, a front section intermediate and unitary with said bottom and top sections, a back section, a longitudinal tab thereon, end sections at each end of bottom section, tabs formed on the edges of said end section opposite said bottom section for folding into the carton, an end section at each end of said top section having tabs thereon for folding into the carton and an extension which projects further from said end section at given points than at other points, and a tab formed as a backward extension of said top section said top being printed to simulate articles in the carton and said tab being printed with an advertising display.

In testimony whereof we have hereunto set our hands.

JOHN J. RYAN.
JOHN GAFFNEY.
